(57) **CLAIM**

The ornamental design for a wall-mounted switch guard, as shown and described.

DESCRIPTION

FIG. 1 is a front left perspective view of a wall-mounted switch guard in accordance with our new design;

FIG. 2 is a front elevation view thereof;

FIG. 3 is a top plan view thereof;

FIG. 4 is a bottom plan view thereof;

FIG. 5 is a left side elevation view thereof, the right side elevation view being a mirror image; and,

FIG. 6 is a rear elevation view thereof.

The broken lines in the figures are for illustrative purposes only and form no part of the claimed design.
